UNITED STATES PATENT OFFICE.

EDWIN H. COSBY, OF DERBY LINE, VERMONT.

GOLF-CLUB STAFF.

Application filed November 2, 1923. Serial No. 672,371.

To all whom it may concern:

Be it known that I, EDWIN H. COSBY, a citizen of the United States, residing at Derby Line; in the county of Orleans and 5 State of Vermont, have invented a new and useful Golf-Club Staff, of which the following is a specification.

This invention aims to provide a staff for a golf club, so constructed that it will 10 possess strength, the staff of the club being provided with a novel grip, which will enhance the hold of the player on the staff of the club.

It is within the province of the disclosure 15 to improve generally and to enhance the utility of devices of that type to which the invention appertains.

With the above and other objects in view, which will appear as the description proceeds, the invention resides in the combination and arrangements of parts and in the details of construction hereinafter described and claimed, it being understood that, within 20 the scope of what is claimed, changes in the precise embodiment of the invention shown, can be made, without departing from the spirit of the invention.

In the accompanying drawings:—

Figure 1 shows in side elevation, a golf 30 club staff constructed in accordance with the invention, parts being successively broken away; Figure 2 is a cross section on the line 2—2 of Figure 1; Figure 3 is a cross section on the line 3—3 of Figure 1.

The golf club staff forming the subject matter of this application includes a core 1 which, preferably, is made of steel, or of some other metal, the core 1 being surrounded by a textile covering 2, which may 35 be in the form of a tube of braided material. About the covering 2 is disposed a casing 3, preferably made of hard wood, the casing being divided into two or more sections. A body 4, made of bamboo, rattan or 40 other like material, is disposed about the casing 3, and is divided radially into a plurality of sections, there being, preferably, more sections in the body 4 than there are in

the casing 3. Adjacent to the handle end of the staff, the body 4 is supplied with longitudinal ribs 5. About the ribbed portion 5 of the body 4 is disposed a tubular grip 6 made of leather, rubber, or other suitable material, the grip being pressed inwardly between the ribs 5 of the body 4 to form 55 external ribs 7 in the grip 6. The constituent parts of the device, constructed as above described, preferably are secured together by glue or cement, and the result is a golf club staff of great strength, a grip being provided which may be grasped readily in the hand of the player to prevent the club from slipping and, it being practically impossible for the grip to become detached from the staff of the club. 65

What I claim is:

1. In a golf club staff, comprising a metal core and a wooden enclosure for the core, the enclosure comprising an inner casing and an outer body, the casing and the body 70 being divided longitudinally and the joints in the casing being disposed in break-joint order with respect to the joints of the body, circumferentially of the staff.

2. A golf club staff comprising a metal 75 core and a wooden enclosure for the core, the enclosure comprising an inner casing and an outer body, the casing and the body being divided longitudinally, the joints of the casing being disposed in break-joint 80 relation to the joints of the body, and a textile covering interposed between the casing and the core.

3. A golf club staff comprising a metal core and a wooden enclosure for the core, 85 the wooden enclosure being provided with longitudinal ribs, and a tubular grip extended about the ribs and cooperating with the ribs to form external ribs in the grip.

In testimony that I claim the foregoing 90 as my own, I have hereto affixed my signature in the presence of two witnesses.

EDWIN H. COSBY.
